UNITED STATES PATENT OFFICE.

ALFRED E. BUHRKE, OF RIVER FOREST, ILLINOIS.

DESIGN FOR A GOLF-CLUB HEAD.

Application filed August 2, 1926. Serial No. 18,571. Term of patent 14 years.

To all whom it may concern:

Be it known that I, ALFRED E. BUHRKE, a citizen of the United States, residing at River Forest, in the county of Cook and State of Illinois, have invented a new, original, and ornamental Design for Golf-Club Heads, of which the following is a specification, reference being had to the accompanying drawing, forming part thereof.

The figure is a front elevation of the head of a golf club, showing the novel portion of my new design.

I claim:

The ornamental design for a golf club head, as shown.

ALFRED E. BUHRKE.
